OTHER PUBLICATIONS

Photograph of fill gun believed to be in use since at least 2012.

Primary Examiner — Philip S Hyder(74) *Attorney, Agent, or Firm* — Talus Law Group LLC(57) **CLAIM**

The ornamental design for the fill gun socket, as shown and described.

DESCRIPTION

FIG. 1 is a perspective view of the fill gun socket showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a perspective view thereof;

FIG. 9 is a perspective view thereof;

FIG. 10 is a perspective view thereof; and,

FIG. 11 is a cross-section thereof, taken along line 11-11 in FIG. 5.

The broken line showings of the fill gun are included for purpose of illustrating environment and form no part of the claimed design.

1 Claim, 11 Drawing Sheets(56)
